(57) **CLAIM**

The ornamental design for a clip case, as shown and described.

DESCRIPTION

FIG. 1 is a perspective view of the new design for a clip case; FIG. 2 is a front view of the clip case; FIG. 3 is a top view of the clip case; FIG. 4 is a bottom view of the clip case; FIG. 5 is a right side view, the left side view being a mirror image thereof; FIG. 6 is a rear view of the clip case; and, FIG. 7 is an enlarged view from FIG. 2 showing the mesh. The dashed lines depict environment and are for illustrative purposes only and form no part of the claimed design.
